HIGH-PRESSURE PUMP

Leon Jean Geeraert, Brooklyn, N. Y., assignor to
 The Geeraert Corporation, New York, N. Y., a
 corporation of New York

Application August 15, 1951, Serial No. 241,925

16 Claims. (Cl. 103—152)

1

The invention relates in general to fluid pumps and has for its principal object the provision of a high pressure pump applicable to various arts and industries but especially suited for use in pumping propellant-chemicals employed in the propulsion of rockets, guided missiles and aircraft, and for the operational discharge of flame-thrower fuel.

In the propulsion of rockets, for example, use is made of fuming nitric acid, hydrogen peroxide, liquid oxygen, fluorine, high-test gasoline, alcohol, ammonia and sulphuric acid, which must be pumped at high delivery pressure with continuous, non-pulsating flow, and must not be exposed to the atmosphere either within the pump itself or anywhere in the conduction system. High pressure, non-pulsating discharge is particularly important in flame-thrower operation. A further complicating condition is the fact that some of the fluids in the above list cannot be pumped safely with conventional pumps of the reciprocating piston or rotary types wherein the fluid being pumped comes into contact with frictional surfaces of piston and cylinder, due to the danger of corrosion.

In the accomplishment of my primary object, I have made use of the fundamental principle of the flexible wall or diaphragm pump and have improved upon known pumps of this type by devising means for attaining sufficiently high pressure delivery and continuity of flow to meet all the exacting requirements which cannot be avoided when pumping propellant-chemicals and flame-thrower fuel, and to render the improved pump otherwise widely useful.

A further object of the invention is to provide a flexible wall pump for the intended purpose which is very compact in structure and possesses a minimum number of operating parts and yet is capable of pumping at high volumetric output capacity.

Another object is to provide a composite pump including a plurality of flexible wall units wherein the primary and secondary control valves for the respective units are so interlocked for synchronized sequential operation of the said units and actuated in direct response to flexible wall action that a high degree of pumping efficiency is attained.

A still further object is to provide a pile organization of individual flexible wall units arranged in-line, wherein the respective units are of interchangeable construction and are separably united in assembled relation in such a manner and by such means that the number of units

2

necessary to afford a required volumetric output capacity may be assembled originally and then desired changes in capacity may be effected readily by simply adding or subtracting units.

Further objects and advantages will become apparent as the following specific description is read in conjunction with the accompanying drawings, in which:

Fig. 1 is a partially diagrammatic cross-sectional view of a simplified form of diaphragm pumping unit constructed in accordance with the invention and having all-electric valve operating means, showing the flexible diaphragm midway between the limits of a suction stroke; and, Fig. 2 is a similar view showing the midpoint of a pressure stroke.

Fig. 3 is a similar view of a pair of diaphragm pumping units of the same nature as that shown singly in Figs. 1 and 2 arranged abreast and representing the midpoints of a suction stroke in one unit and of a pressure stroke in the other; and, Fig. 4 is a similar view but showing reversal of strokes in the respective units.

Fig. 5 is a partially diagrammatic cross-sectional view of a modified form of double unit having long-thrust diaphragms and electrically actuated hydraulic pilot valves for operating the control valves, showing the midpoints of a suction stroke in one unit and of a pressure stroke in the other; and, Fig. 6 is a similar view representing the reverse operational condition.

Fig. 7 is an end elevation of a short-thrust, multiple pile pump wherein a plurality of individual diaphragm pumping units are arranged in axial alignment; Fig. 8 is a side elevation of the same; and, Fig. 9 is an exploded fragmentary side elevation thereof.

Fig. 10 is a partially diagrammatic horizontal cross-sectional view of a multiple pile pump of the type illustrated in Figs. 7 to 9 but composed of only two piles of two diaphragm pumping units each, showing the pump in operation with one pile at the end of a suction stroke and the other at the end of a pressure stroke; and, Fig. 11 is a similar view showing the reverse operational condition.

Fig. 12 is a large-scale axial cross-section view of a single diaphragm pumping unit of the short-thrust form illustrated in Figs. 7 to 11, wherein a biasing and reinforcing spring is applied to the diaphragm thereof; Fig. 13 is a fragmentary exploded view of the unit; and, Fig. 14 is a fragmentary perspective view of diaphragm and spring alone.

Fig. 15 is an enlarged fragmentary front eleva-

tion of the multiple pile cylinder of Figs. 7, 8, 10 and 11, partly broken away and in section to show portions of the various casing sections and other related elements in elevation; and, Fig. 16 is a similar view showing particularly the inner face of one of the casing sections.

Fig. 17 is a detail view in axial vertical cross-section of the flexible wall pumping units alone of a double-unit pump wherein the flexible wall is in the form of an elastic thimble-like tube closed at one end, showing the lefthand unit at the start of a pressure stroke and the righthand unit at the start of a suction stroke; Fig. 18 is a similar view showing the lefthand and righthand units respectively substantially midway during their pressure and suction strokes; and Fig. 19 is a similar view showing the lefthand and righthand units at the end of their respective pressure and suction strokes.

Fig. 20 is a vertical axial cross-sectional view of a complete double-unit pump embodying the elastic tube form of flexible wall but in a modified form, showing the lefthand unit approaching the end of a pressure stroke and the righthand unit at the completed end of a suction stroke; Fig. 21 is a similar view showing the lefthand unit at the end of a suction stroke and the righthand unit approaching the end of a pressure stroke; Fig. 22 is a horizontal cross-sectional view taken on line 22-22 in Fig. 20; Fig. 23 is an enlarged detail fragmentary view, partly in vertical section, of the upper end of one of the units at the end of a pressure stroke; and, Fig. 24 is an enlarged fragmentary view, partly in vertical section, of the control valve to show the dwell latch in detail.

Fig. 25 is a horizontal cross-sectional view similar to Fig. 22 of a quadruple unit pump of the same type as that shown in Figs. 20 to 24, inclusive.

Before proceeding with detailed description of my improved pump, it will be reiterated that, while the developed pump has wide general application in the arts and industries, I was expressly seeking to devise a pump especially suited for use with propellant-chemicals and flame-thrower fuel for military purposes. Therefore, some of the exacting operational requirements peculiar to the specific employment I had in mind will be more explicitly enumerated. For instance, the pressure on the fluid in the tank of origin from which it is to be pumped to another tank or other point of destination must not exceed that of the atmosphere (14.7 p. s. i. at sea level). In other words, pressurizing the tank of origin is forbidden. Furthermore, gauge pressure at the discharge side of the pump must be at least 100 p. s. i., and the condition of flow through the pump and all chambers or channels of the conduction system from tank of origin to point of destination must be such that cavitation and the resultant danger of vapor-lock are avoided.

As previously stated, I have chosen to adapt the fundamental principle of the flexible wall pump to my purpose, one reason being that in such a pump there is no communication between the fluid being pumped and the driving fluid in the primary circulation system, whereby it is practicable to maintain the entire secondary conduction system for the propellant-chemicals and the like closed to the atmosphere.

The above-mentioned and other advantages of the flexible wall pump principle for my purpose should be fully appreciated upon consideration of the simple one-diaphragm pump unit constructed in accordance with the invention which is illus-

trated in Figs. 1 and 2 of the drawings. With the understanding that like reference characters indicate corresponding parts in the several views, the numeral 20 designates the pump casing, which is composed of two substantially identical circular dished sections 31 and 32 arranged to present their concave faces toward each other to form opposed working chambers 33 and 34, respectively, separated in a fluid-tight manner by flexible wall 35, which in this instance is a diaphragm. The flexible wall or diaphragm 35 is marginally clamped between the peripheral portions of casing sections 31-32 and is represented as being annularly corrugate in form and at the midpoint of its travel.

By using a separable flexible wall or diaphragm, it is practicable to make the said wall of a plastic or other specific material which will not be corroded or otherwise affected adversely by any particular propellant-chemical fluid. In like manner, the secondary section of the pump casing and all fluid conduits in the secondary conduction system may be made of stainless steel or other metals inert to the propellant-chemicals, whereas cast iron or other less expensive metals may be used in fabrication of all fluid conducting parts of the primary circulation system and the primary casing section.

Casing sections 31 and 32, respectively, are provided with two-way ports 36 and 37 communicating with the respective working chambers 33 and 34. These ports preferably are axially disposed and therefore in alignment. Control valves for ports 36 and 37, respectively, are indicated at 38 and 39. The respective casings 40 and 41 of control valves 38 and 39 preferably are formed integral with pump casing sections 31 and 32 and have internal cylindrical chambers 42 and 43 in which valve plungers 44 and 45, respectively, are 40 slideable longitudinally. For reasons which will appear presently, it is preferred to arrange valve chambers 42 and 43 in axial parallelism.

In the outer portion of valve casing 40 of control valve 38 there are two ports 46 and 47, which may be termed "pressure" and "suction" ports respectively because they are intended to be connected as shown with the respective pressure and suction lines 48 and 49 of a suitable primary circulation system (not shown) that generates power to drive the pump diaphragm 35. It is not considered to be necessary to disclose details of the said primary circulation system, for the reason that I am not claiming anything new in that system. Any conventional primary system with its prime mover (not shown) for generating pressure and suction conditions in the respective lines 48 and 49 will serve my purpose.

Valve plunger 44 of control valve 38 has an annular peripheral channel 50 which is of such axial width and disposition that, when the plunger is in its righthand position shown in Fig. 1, it will span ports 47 and 36, and, when in its lefthand position (Fig. 2), will span ports 46 and 36, whereby two-way port 36 may be connected selectively by longitudinal shifting of valve plunger 44 with either pressure port 46 or suction port 47.

Casing 41 of control valve 39 also has two ports 51 and 52 which are intended to be connected as shown with intake line I and delivery line D of the secondary conduction system (not shown) that leads from the tank of origin (not shown) to the pump and thence to a point of destination (not shown). Valve plunger 45 also has an annular peripheral channel 53 of such axial width

and disposition that, when said plunger is in its lefthand position shown in Fig. 1, it will span ports 51 and 37, and, when in its righthand position (Fig. 2), will span ports 52 and 37, whereby two-way port 37 may be connected selectively by longitudinal shifting of valve plunger 45 with either intake port 51 or delivery port 52.

The respective plungers 44 and 45 of control valves 38 and 39 are shifted longitudinally by solenoids 54 and 55, both of which have their field coils connected in each of two parallel electric circuits. The field coil of one solenoid is wound oppositely to that of the other solenoid so that both solenoids will operate in opposite directions to move the valve plungers correspondingly whenever current is caused to flow through either of said parallel circuits. The polarity of the two parallel circuits is controlled by reversing micro-switches of standard type 56 and 57. In other words, when micro-switch 57 is closed, as shown in Fig. 1, solenoid 54 will be energized in a manner which will shift plunger 44 of control valve 38 to the righthand limit of its path of shifting movement, whereas simultaneous energization of solenoid 55 will shift plunger 45 of control valve 39 in the opposite direction. Conversely, closing of reversing micro-switch 56, as shown in Fig. 2, to reverse the polarity of current flowing through both solenoid field coils will shift the plungers of both control valves in reverse directions to correspondingly change the direction of flow of fluids through said valves. It is to be understood, however, that the specific electric circuits represented in Figs. 1 and 2 are purely illustrative. Some other circuit arrangement may be employed provided that the solenoids shift the respective control valve plungers in opposite directions alternately when the micro-switches are triggered into circuit closing condition.

At this juncture, it may be appropriate to define some constantly recurring terms used in the specification and claims. For instance, the power imparting or driving fluid in the primary circulation system will consistently be called the "primary fluid," regardless of its specific nature. Similarly, the propellant-chemical or other fluid to be pumped through the secondary conduction system will be known as the "secondary fluid." For the same reason, working chambers 33 and 34 of the pump will be called, respectively, the "primary working chamber" and the "secondary working chamber," and control valves 38 and 39 will be termed the "primary control valve" and the "secondary control valve," respectively.

In this one-diaphragm embodiment of the invention, micro-switches 56 and 57 are triggered for automatic sequential shifting of the plungers of the primary and secondary control valves in opposite directions at the completion of each diaphragm stroke by means responsive to working chamber pressure. For this purpose, each micro-switch has a pressure-sensitive plunger or piston which is exposed to fluid pressure in the corresponding working chamber of the pump. For this purpose, the pressure-sensitive plunger 56' of micro-switch 56 is located for longitudinal reciprocation in fluid duct 58 which communicates with the interior of primary working chamber 33 in the vicinity of port 36. Similarly, the pressure-sensitive plunger 57' of micro-switch 57 is located for reciprocation in fluid duct 59 which communicates with the interior of secondary working chamber 34 close to port 37. Micro-switch 56 is constructed and adjusted to be trig-

gered into close condition when the pressure in primary chamber 33 reaches a predetermined degree at the end of each upward suction stroke of diaphragm 35, whereas micro-switch 57 is constructed and adjusted to be triggered when the pressure in secondary working chamber 34 reaches a predetermined degree at the end of each downward pressure stroke.

The operation of the one-diaphragm unit should be understood upon further reference to Figs. 1 and 2. Assuming that the primary and secondary control valves 38 and 39 were shifted into the positions shown in Fig. 1 by reversal of the solenoid circuits as a result of automatic triggering of micro-switch 57 at the end of a preceding downward primary pressure stroke, primary working chamber 33 will have been opened to suction line 49 of the primary circulation system. This action permitted low pressure primary fluid to exert a suction effect on primary working chamber 33 and thereby commence to draw diaphragm 35 on its upward suction stroke. Fig. 1 shows diaphragm 35 at the mid-point of its travel in that direction. During this suction stroke, secondary fluid will be drawn into secondary working chamber 34 from secondary intake line I. At the end of the suction stroke just described, micro-switch 56 will be triggered automatically to cause reversal of current in solenoids 54 and 55, thereby shifting the plungers of primary and secondary control valves 38 and 39 into the positions represented in Fig. 2. As a result of this valve action, movement of secondary fluid from intake line I into secondary working chamber 34 will have been checked and said secondary working chamber will have been opened to secondary delivery line D as indicated. Simultaneously, primary working chamber 33 will have been opened to primary pressure line 48 to permit entry of primary fluid under high pressure. This action will cause diaphragm 35 to be thrust downward and thereby force secondary fluid from secondary working chamber 34 into secondary delivery line D at high pressure. Fig. 2 shows diaphragm 35 at the mid-point of this downward travel.

When diaphragm 35 again reaches the downward limit of its travel in a pressure stroke, the two-stroke cycle of the pumping action will have been completed.

In the simplified, one-diaphragm unit just described, delivery of secondary fluid through line D will be intermittent, there being suspension of flow in the delivery line throughout each suction stroke.

Referring now in detail to Figs. 3 and 4, continuous, non-pulsating flow in the delivery line has been achieved by virtually combining two of the simple pump units illustrated in Figs. 1 and 2 for coordinated operation through interlocking of the respective primary and secondary control valves thereof for sequential reciprocation of their plural diaphragms in opposite directions in a distinctly improved embodiment of the invention. It is as if the unit shown in Fig. 1 were used in the same position as lefthand unit A in Figs. 3 and 4, and as if the unit in Fig. 2 were reversed end for end horizontally and put in the position of righthand unit B in Figs. 3 and 4. The same reference characters for corresponding parts have been retained, except that the letters *a* and *b* have been affixed to denote location in either unit A or unit B, respectively.

In order to effect the desired interlocking operation of the control valves, plungers 44a-44b

of primary control valves 38a—38b have been rigidly united for conjoined movement by connecting rod 60, and plungers 45a—45b of secondary control valves 39a—39b are similarly united by connecting rod 61. The desirability of arranging the working chambers of the control valves in parallelism should now be apparent. As a result, connecting rods 60 and 61 are free to reciprocate side by side in opposite directions when actuated by solenoids 54a—54b—55a—55b in the manner which will be described presently in relation to the operation of the pump. In this instance, solenoids 54a—54b are electrically connected in series in one circuit and solenoids 55a—55b are in series in another circuit, the two circuits preferably being in parallel. There are only two micro-switches for the entire two-unit pump and, in this instance, both are triggered by predetermined pressure conditions in the secondary working chambers 33a—33b only at the ends of the respective pressure strokes, which is a distinct advantage under some pumping conditions because valve shifting cannot take place before complete evacuation of secondary fluid. However, in certain situations, synchronization of motion of the two diaphragms may not be obtained, thereby necessitating the use of micro-switches in the primary chambers as well as in the secondary chambers, in which case both switches for each unit would be electrically connected in series to avoid low volumetric efficiency.

Operation of the double-unit pump disclosed in Figs. 3 and 4 will now be described. Referring first to Fig. 3, it will be observed that diaphragm 35a of the lefthand unit A is at the midpoint of its upward suction stroke while secondary fluid is being drawn from secondary intake line I, whereas diaphragm 35b of righthand unit B is midway in its downward pressure stroke in which secondary fluid is being forced into secondary delivery line D. When diaphragm 35b of unit B reaches the end of its downward pressure stroke, the pressure in duct 59b will have attained the predetermined degree for triggering of micro-switch 57b. When this occurs, the electric circuit of solenoids 54a and 55b will be closed (indicated by heavy circuit lines in Fig. 3) to cause valve plungers 44a—44b and 45a—45b to be shifted simultaneously in opposite directions into the dwell positions shown in Fig. 4. Immediately upon reversal of the control valves at the end of the pressure stroke in unit B, unit A will commence instantly to force into secondary delivery line D the increment of secondary fluid that was drawn into working chamber 34a during the preceding suction stroke. Simultaneously, unit B will be undergoing a suction stroke. Now, when diaphragm 35a of unit A completes its upward pressure stroke, the pressure in duct 58a will have attained the predetermined degree for triggering of micro-switch 55a. When this occurs, the electric circuit of solenoids 55a and 54b will be closed (heavy circuit lines in Fig. 4) to cause valve plungers 44a—44b and 45a—45b to be shifted reversely into the dwell positions shown in Fig. 3, thus completing the cycle of operation. It should be obvious that in this double-unit pump there will be uninterrupted, non-pulsating flow of secondary fluid in the delivery line as compared with the pumping action of the single unit disclosed in Figs. 1 and 2.

In Figs. 5 and 6, there is illustrated a double-unit pump of modified construction. This embodiment of the invention differs from that dis-

closed in Figs. 3 and 4 principally in the form and size of each pump casing and the flexible walls therein, the increased length of stroke and proportionately greater displacement, the substitution of fluid-pressure for solenoid action as the direct actuating means for the control valves, and the use of mechanical diaphragm-contacting trigger devices.

The casing sections 31—32 of both units A and B are bell-shaped and the flexible walls or diaphragms 35—35 are of similar shape, whereby long-stroke, high-displacement pumping action is achieved. The control valves 38—39 are identical in construction and arrangement with those in the Figs. 3 and 4 embodiment, but their plungers 44a—44b—45a—45b are not affixed to the solenoid cores. Instead, the cores of the primary solenoids 54a and 54b of the respective units A and B are affixed to pilot valve plungers 62a and 62b respectively, which operate reciprocatingly in valve sleeves 63a and 63b located across the outer ends of valve cylinders 40a and 40b and constituting cylinder heads therefor. Similarly, the cores of secondary solenoids 55a and 55b of the respective units A and B are affixed to pilot valve plungers 64a and 64b respectively, which are adapted to reciprocate in valve sleeves 65a and 65b located across the outer ends of valve cylinders 41a and 41b and constituting cylinder heads therefor. Each valve sleeve 63a—63b—65a—65b has two axially spaced diametrical ports 66 and 67 which pierce the inner and outer walls of the respective sleeves in axial registration with the respectively adjacent outer ends of the corresponding working chambers of the control valves 38—39. Each of the valve plungers 62a—62b—64a—64b has a diametrical port 68 which is adapted to register with and interconnect the inner and outer wall portions of port 66 when the said valve plunger is in its elevated position and to register with and interconnect the inner and outer wall portions of the other port 67 when the plunger is in its outwardly projected position. Valve plungers 62a—62b—64a—64b gravitate into their depressed positions when the fields coils of solenoids 54a and 54b become de-energized, whereas energization of said solenoids serves to raise the respective valve plungers to their elevated positions.

Due to the modification just described, plungers 44a—44b and 45a—45b of the respective control valves 38a—38b and 39a—39b have also become pistons which may utilize the motive power of primary fluid in primary pressure and suction lines 48 and 49 as means for causing their operative reciprocation in the performance of their original control functions in relation to ports 46—47—36 and ports 51—52—37. Shifting of the piston-plungers 44a—44b and 45a—45b back and forth in opposite directions in interlocked relation through utilization of the primary fluid is now under the control of pilot valves 69a, 69b, 70a and 70b, of which: valve 69a is constituted by parts 62a—63a—66a—67a—68a operated by solenoid 54a; valve 69b is constituted by parts 62b—63b—66b—67b—68b operated by solenoid 54b; valve 70a is constituted by parts 64a—65a—66a—67a—68a operated by solenoid 55a; and valve 70b is constituted by parts 64b—65b—66b—67b—68b operated by solenoid 55b.

In order to connect the respective pilot valves of unit A with primary fluid, ports 66a—66a of valves 69a—70a are connected direct to primary pressure line 48 by duct forming means 72a, and ports 67a—67a of said valves are connected di-

rect to primary suction line 49 by duct forming means 71a. Similarly in pump unit B, ports 66b—66b of pilot valves 69b—70b are connected direct to primary suction line 49 by duct forming means 71b, and ports 67b—67b of said valves are connected direct to primary pressure line 48 by duct forming means 72b.

While in the diagrammatic representation of Figs. 5 and 6 the duct forming means 71a—72a—71b—72b is in the nature of external tubing, it is within the scope of the invention to substitute internal ducts cast or drilled in the pump casing.

Synchronized triggering of the pilot valves of pump units A and B, respectively, is accomplished automatically by micro-switches 73a and 73b, which are installed in the outer end portions of working chambers 34a—34b and have spring-retracted (opening) pushbuttons 74a—74b, respectively, which normally project into the interior of said chambers in the path of said flexible walls when the switches are open. Contact of the flexible wall of one of the units with the corresponding pushbutton at the end of its pressure stroke will serve to close the micro-switch of which said pushbutton forms a part. Thereafter, movement of the flexible wall in reverse direction (suction stroke) will permit the switch to open automatically through spring action. Micro-switch 73a serves to open and close parallel electric circuits 75 and 76 which are energized by battery 77 or other suitable source of current. The field coils of solenoids 54b and 55a are connected in circuits 75 and 76, respectively. On the other hand, micro-switch 73b serves to open and close parallel electric circuits 78 and 79 which also are energized by source 77. The field coils of solenoids 54a and 55b are connected in circuits 78 and 79, respectively.

Although counteracting fluid pressures will tend to secure the piston-plungers of the respective control valves in their different dwell positions assumed at the end of each pressure stroke, it is desirable to supplement the pressure means by more positive mechanical means. Any suitable latch means may be adopted for this purpose, but I have shown, for purposes of illustration, the simple spring-urged detents 80 and 81 which enter the alternative notches 82 and 83 provided in connecting rods 66 and 67, respectively. These dwell latches, as they may be termed, will become disengaged readily when the valve piston-plungers are subjected to pressures of primary fluid in the same direction through operation of the appropriate pilot valves.

The operation of the modified pump will now be described. Whereas plungers 62a—62b—64a—64b of the respective pilot valves 69a—69b—70a—70b are all in their depressed positions throughout almost the entire period of each stroke of the pump, they will be operated selectively at appropriate times during each operational cycle. Assuming now that flexible wall 35a of unit A has just completed its downward pressure stroke at the end of a cycle, contact of the said flexible wall with plunger 74a of micro-switch 73a will have triggered pilot valves 69b and 70a by closing the circuits of solenoids 54b and 55a, respectively. Triggering of pilot valves 69b and 70a causes plungers 62b and 64a, respectively thereof to be thrust into their elevated positions shown in Fig. 5. When this happens, the left end of chamber 43a of control valve 39a is opened through ports 66—68

and duct forming means 71a to primary suction line 49, which will cause coupled control valve piston-plungers 45a—45b to shift to the lefthand dwell position shown. There will be no hydraulic resistance to this movement because the outer (right) end of chamber 43b of control valve 39b will still be open to communication with primary pressure line 48 as shown. At the same time, the right end of chamber 42b of control valve 38b will be opened through ports 66—68 and duct forming means 71b with primary suction line 49. Since the left end of chamber 42a of control valve 38a is still in communication with primary pressure line 48, the desired shifting of coupled control valve piston-plungers 44a and 44b to the righthand dwell position shown will occur.

It is not so shown in Fig. 5, but plungers 62b and 64a of pilot valves 69b and 70a will have gravitated into their depressed positions just as soon as the pushbutton 74a of micro-switch 73a has been released by flexible wall 35a at the start of its upward suction stroke toward the mid-position actually shown. Upon return of plungers 62b and 64a of pilot valves 69b and 70a to their depressed positions (not shown), the right end of chamber 42b of control valve 38b and the left end of chamber 43a of control valve 39a will both be opened to primary pressure line 48, but the pressure thereof will be balanced by the same pressure to which the opposite ends of piston-plungers 44a and 45b of control valves 38a and 39b, respectively, are subjected because pilot valves 69a and 70b are always open to pressure when their plungers are depressed. In fact, all pilot valves are open to pressure when their plungers are depressed and open to suction when their plungers are elevated through energization of their respective solenoids.

At the end of the first stroke of the pumping cycle under consideration, flexible wall 35b will have closed micro-switch 73b to energize solenoids 54a and 55b and thereby open the left end of chamber 42a and the right end of chamber 43b to primary suction, as shown in Fig. 6, which will cause coupled control valve piston-plungers 44a—44b to shift to the lefthand dwell position shown in Fig. 6 and the coupled control valve piston-plungers 45a—45b to shift in the opposite direction to the righthand dwell position shown. Of course, by the time the flexible walls 35a—35b have reached the mid-positions shown, solenoids 54a and 55b will have become de-energized and pilot valves 69a and 70b will have been opened to primary pressure. The cycle will be completed when flexible walls 35a and 35b have reached the ends of their respective pressure and suction strokes shown in Fig. 6.

Figs. 7 to 16, inclusive, illustrate the preferred embodiment of the invention, which achieves a high degree of simplicity, compactness, efficiency of operation, and versatility. In brief, the casing sections of each pumping unit are in the form of flat, comparatively thin, circular plates having very shallow working chambers and short-stroke flexible diaphragms. These plates, in the required number and cooperative combinations, are adapted to be bound together in a compact "in-line" pump organization to afford the required number of piles for a particular volumetric output capacity which may be needed. To increase or decrease the capacity, all that is necessary is to add or subtract one or more diaphragm chambers. Furthermore, all units are identical in structure and thus interchangeable. A partic-

ular advantage of this interchangeability is the facility with which casing sections and diaphragms of different composition may be exchanged to accommodate propellant-chemicals of different corrosion characteristics.

As shown in Figs. 7 and 8, in particular, the completely assembled "in-line" organization of piles has the general form of a cylindrical casing 80 disposed with its axis horizontal on a flat supporting base 81 of suitable length and anchored to the latter in a manner which will be described presently.

Turning now to Figs. 10 and 11, it will be observed that the illustrative pump organization comprises two piles and thus may be termed appropriately a "twin pile pump." The two piles are located on opposite sides of an anchor plate 82 which is suitably affixed to base 81 midway between its ends, and head plates 83 and 84 embrace the outer ends of said piles. As shown in Figs. 7 to 9, the assembled piles and plates 82, 83 and 84 are clamped together in precise alignment and rigidity by tie bolts 85.

Each pile comprises two pump casing units (Figs. 10 and 11) and each unit in turn is composed of mated casing sections 86 and 87 which are circular in general form and nearly identical in specific structure. One of the units is shown clearly in detail in Figs. 12 to 14. The left-hand casing section 86 (Figs. 12 and 13) has a comparatively shallow concavity formed in its inner (right) face to constitute the primary working chamber 88 of the unit. (Compare the axial depth of chamber 88 with that of the corresponding chambers represented in Figs. 5 and 6 or even in Figs. 1 to 4.) The shallow secondary working chamber 89 formed in the inner (left) face of casing section 87 differs from primary working chamber 88 principally in the provision of an annular depression 90 of uniform depth which extends radially inward from the peripheral margin of said chamber approximately half-way to its central axis. Casing section 86 is provided with an annular groove 91 around the margin of primary working chamber 88. This groove 88 has a cylindrical peripheral wall 92 and preferably serrated side face 93. Casing section 87 has a narrow and deep cylindrical groove or cut 94 substantially flush with the outer wall of groove 91 of section 86.

Circular flexible diaphragm 95 separates primary working chamber 88 from secondary working chamber 89 and has its marginal edge gripped between casing sections 86 and 87 when assembled. A serrated marginal bead 96 on diaphragm 95 is adapted to fit snugly and securely in groove 91.

Casing sections 86 and 87 are provided with central grilles ports 97 and 98, respectively, of large cross-sectional area. Casing section 86 also has a shallow annular cavity or depression 99 in its outer face surrounding port 97 in preferably eccentric relation thereto. Leading radially outward from the outermost part of cavity 99 is an outwardly enlarged groove 100 of semi-circular cross-section which opens through the peripheral edge face of casing section 86. Port 97, cavity 99 and groove 100 are so constructed and arranged that they will register with these same indentations in the adjacent casing section 86 of the cooperative unit of a pile when assembled in the closely abutting relation shown in Figs. 10 and 11. In this assembled relation, cavities 99-99 and grooves 100-100 of both abutting casing sections 86-86 unite to form cir-

75 12
cular radial conducting passages 101 for primary fluid.

Each casing section 87 has a shallow, eccentric cavity 102 in its outer face surrounding port 98. From the outermost part of cavity 102, a radial, outwardly enlarged groove 103 of semi-circular cross-section leads to and opens into an axial passage 104 located near the periphery of said casing section 87. Actually, cavity 99 and groove 100 of casing section 86 are identical in form with cavity 102 and groove 103 of casing section 87, but, in the assembled relation of both casing units of a pile (Figs. 10 and 11), they are disposed so that grooves 100 and 103 extend in diametrically opposite directions from the pile axis. Casing section 86 also is provided further with an axial passage 105 near its outer peripheral edge which is adapted to register with passage 104 of casing section 87 when said sections are assembled. A short radial groove 106 of semi-circular cross-section leads outward from the outer end portion of passage 104 through the peripheral edge face of casing section 86. In the assembled relation of both casing units of a pile, the grooves 100-106 of the abutting sections 86-86 of said casing units combine to form a circular passage 107.

It having been found in practice that the most suitable hydraulic pump for use as prime-mover (not shown) in the primary circulation system was incapable of pulling more than from one to three pounds of vacuum (13.7-11.7 PA), the pressure differential between the primary side of a pump diaphragm during a suction stroke and the pressure in the tank of origin (atmospheric pressure) is only about one to three pounds. Therefore, in order to compensate for the low suction pressure and to insure a quick, non-lagging suction stroke of each diaphragm, I have added suction-stroke bias to each diaphragm by applying thereto spring means which is shown in detail in Figs. 12 to 15, inclusive. A practical embodiment of the biasing means just mentioned is the generally annular spring 108 which includes a circumferential base ring 109 adapted to have its opposite side edge portions fit in grooves 91 and 94 of casing sections 86 and 87 when assembled to form a casing unit. A web 110, which lies in a plane perpendicular to the casing axis, projects inward from base ring 109 and is adapted to be disposed on the secondary working chamber side of diaphragm 95. Web 110 is provided with substantially radial fingers 111 projecting inward therefrom. In order to increase the flexibility of fingers 111, they are provided with longitudinal slots 112 which open into holes 113 located in web 110 close to base ring 109. Considerable space between fingers is required in order to prevent overlapping of the fingers and danger of pinching the diaphragm while passing dead center.

In addition to the primarily intended biasing of diaphragm 95, spring 103 serves other useful purposes. It tends to preserve the smooth shape of diaphragm 95 and prevent excessive deformation such as would be likely to result eventually in creasing and rupture; and it absorbs and conducts heat from the diaphragm to the peripheral portions of the casing for external radiation.

Referring again to Figs. 10 and 11, it will be observed that the adjacent faces of anchor plate 82' and of head plates 83' and 84' cooperate with cavities 102 and grooves 103 of casing sections 87 to wall them in completely and thereby provide radial fluid passages 114.

The primary and secondary control valves 115 and 116 for the twin pile preferably are located in horizontal parallelism on opposite sides of the cylindrical casing 80'. Primary valve 115 includes a tubular casing 117 closely abutting the peripheral edges of the respective sections of all casing units. Valve casing 117 may be supported by plates 82'-83'-84 in any manner which may be expedient. A single elongated valve plunger 118 is mounted to reciprocate in the interior chamber 119 of valve casing 117 from one extreme dwell position to the other. Suitable detent means 120 is provided to secure valve plunger 118 yieldably in either dwell position until overcome by the operating force which shifts said valve plunger in its normal operation. Ports 121 and 122 are provided in valve casing 117 for registration with the respective passages 101-101 of the lefthand and righthand piles which make up the twin organization. Primary suction and pressure ports 123 and 124 are provided in valve casing 117 adjacent to each of passages 101-101 for connection to the respective suction and pressure lines 48 and 49 of the primary circulation system. Valve plunger 118 has appropriately spaced annular peripheral grooves or channels 125 and 126 which, in the righthand dwell position of said plunger (Fig. 10), are adapted to span and thereby interconnect ports 121-49 and ports 122-48, respectively, and, in the opposite lefthand dwell position (Fig. 11) to span and interconnect ports 121-48 and ports 122-49, respectively.

Valve plunger 118 is affixed to the cores of solenoids 127 and 128. When energized, solenoid 127 is adapted to move valve plunger 118 to the left, and solenoid 128 is adapted to move said plunger in the opposite direction.

Control valve 116 also includes a tubular casing 129, in the chamber 130 of which elongated valve plunger 131 is mounted to reciprocate between extreme dwell positions. Suitable detent means 132 also is provided to secure valve plunger 131 yieldably in either dwell position. Ports 133 and 134 in casing 129 are positioned to communicate with passages 107-107 of the respective lefthand and righthand piles of the composite twin. Primary delivery and intake ports 135 and 136 are provided in valve casing 129 adjacent to each of the ports 107-107 for connection, respectively, with secondary delivery line D and intake line I. Valve plunger 131 is provided at appropriate intervals with peripheral annular grooves or channels 137 and 138 which, in the lefthand dwell position (Fig. 10) are adapted to span and thereby interconnect ports 135-133 and ports 136-134, respectively, and, in the opposite righthand dwell position (Fig. 11), to span and interconnect ports 136-133 and ports 135-134, respectively.

Valve plunger 131 is affixed to the cores of

solenoids 139 and 140. When energized, solenoid 139 is adapted to move valve plunger 131 to the right and solenoid 140 is adapted to shift said plunger in the opposite direction.

- 5 A micro-switch 141 is mounted on head plate 83' and has a pushbutton 141' projecting normally into secondary working chamber 89 of the adjacent pump pile when said switch is open for actuating contact by the adjacent diaphragm 95 at the completion of its pressure stroke. Micro-switch 141 is connected electrically with solenoids 127 and 140 in such a manner that closing of the switch will energize both of said solenoids and thereby cause primary and secondary valve plungers 118 and 131 to be shifted synchronously in opposite directions into their respective left-hand and righthand dwell positions.

- A micro-switch 142 is mounted on the opposite head plate 84 and has a pushbutton 142' projecting normally into secondary working chamber 88 of the adjacent pump pile when said switch is open for actuating contact by the adjacent diaphragm 95 at the completion of its pressure stroke. Micro-switch 142 is connected electrically with solenoids 128 and 139 in such a manner that closing of the switch will energize both of said solenoids and thereby cause primary and secondary valve plungers 118 and 131 to be shifted synchronously in opposite directions into their respective righthand and lefthand dwell positions.

The operation of the twin pile should be understood readily upon further reference to the two operating cycles represented in Figs. 10 and 11.

- 35 Fig. 10 shows the diaphragms and interlocked control valve settings at the end of a cycle in which the two cooperative diaphragms of the lefthand pile have just completed their joint pressure stroke, in which they moved apart from each other, and the two cooperative diaphragms of the righthand pile have just completed their joint suction stroke, in which they closed toward each other. Valve plungers 118 and 131 are shown during the instant when micro-switch 45 141 is closing the circuits of solenoids 127 and 140 and the latter are on the point of shifting said valve plungers in opposite directions to the new dwell positions represented in Fig. 11.

- When the shift occurs, control valve 115 will 50 connect primary working chambers 88-88 of the lefthand pile with primary suction line 43 through the medium of port 123, plunger channel 125, passage 101, and both ports 97-97. Simultaneously, control valve 115 will connect primary working chambers 88-88 of the right-hand pile with primary pressure line 49 through the medium of port 124, plunger channel 125, passage 101, and both ports 97-97. Application of suction and pressure in this manner will 55 cause the cooperative diaphragms of the lefthand pile to close toward each other into the positions shown in Fig. 11, whereas the diaphragms of the righthand pile will move apart into the positions shown. During this motivating action by primary fluid, secondary fluid will be moved in the direction of the arrows in Fig. 11, i. e. secondary fluid will be drawn from secondary intake line I in the direction of the arrows through port 136, valve channel 131, port 60 133, passages 107-104-114, and both ports 98-98 into secondary working chambers 89-89 of the lefthand pile. At the same time, previously captivated secondary fluid will be pressurized and then expelled in pressurized condition from secondary working chambers 89-89

of the righthand pile in the direction of the arrows through ports 98—98, passages 114—105—107, ports 134, valve channel 138, and port 135 into secondary delivery line D.

At the end of the second cycle represented in Fig. 11, the pushbutton 142' of micro-switch 142 has been pushed inward by the adjacent diaphragm 95 and solenoids 128 and 139 are going into action to reverse the interlocked control valves 115 and 116 and thereby start the diaphragms of the respective piles through the cycle represented as just ending in Fig. 10. During this two-stroke cycle, the primary and secondary fluids moved in the direction of the arrows.

It should now be understood that in the twin pile illustrated in Figs. 10 and 11, the cooperative pairs of diaphragms of both piles pulsate in a bellows-like action alternately toward and away from each other. The stroke is very short, but maximum volumetric output capacity is realized for the small size and weight of the pump as a whole. Due to this characteristic, the multiple pile organization renders the pump well suited for installation in the cramped interior of rockets and other aerial projectiles and aircraft for use in delivering propellants from contained tanks to burners or other delivery points either preceding flight or during flight under radio control, as well as for external use with ground equipment. A still further use for which the multiple pile pump is well suited is for pressurizing of fuels in the servicing of large military flame throwers.

In Figs. 17 to 19, inclusive, there are shown in three successive operational stages the flexible wall units alone of a modified double-unit pump, wherein the flexible walls are elastic as well as flexible and are intended to function through alternate distention and contraction.

Referring first to Fig. 17, the double-unit pump comprises lefthand unit A and righthand unit B, which retain their relative positions in Figs. 18 and 19. Both units are identical in construction when in the condition represented in unit A (Fig. 17) in which the flexible wall member is contracted. The respective casings 143a and 143b are open-ended cylinders having reduced externally screw-threaded necks 144a—144b and 145a—145b at their lower and upper ends, respectively, for engagement with clamping rings 146a—146b and 147a—147b which secure said casing necks 144a—144b and 145a—145b, respectively, to the externally flanged necks 148a and 148b of two-way primary ports 149a and 149b and to similar necks 150a and 150b of secondary ports 151a and 151b of the respective primary and secondary control valve casings (not shown). At the lower base ends of casings 143a and 143b, the externally flanged base ends of tubular collapse-preventing forms 152a and 152b are clamped between the externally flanged ends of port necks 150a and 150b and the lower edges of casing necks 144a and 144b, respectively. These collapse-preventing forms 152a and 152b project into casings 143a and 143b and extend throughout almost the entire length of the interior of said casings. Forms 152a and 152b have numerous fluid-penetrable perforations 153a and 153b from their bases to their upper ends, which latter are provided with smoothly convex caps 154a and 154b having central perforations 155a and 155b therein. Enclosing collapse-preventing forms 152a and 152b are flexible wall members 156a

70
75

and 156b, respectively, which are thimble-shaped in form and, in their normal relaxed condition, closely fit the respective collapse-preventing forms in the manner shown in the lefthand unit A (Fig. 17), wherein the closed upper end of flexible wall member 156a is seated on cap 154a of form 152a. The open base ends of flexible wall members 156a and 156b are tightly gripped between the downwardly flared outer surfaces of the base portions of collapse-preventing forms 152a and 152b, respectively, and the internal surfaces of the casing necks 144a and 144b, which are correspondingly outwardly flared. To make the connection of the base portions of flexible wall members 156a and 156b with casing necks 144a and 144b even more secure, the former are downwardly thickened and externally serrated for interlocking engagement with correspondingly serrated inner surfaces of the latter.

An important structural feature of flexible wall members 156a and 156b is the fact that they are made of elastic material, such as rubber or a rubber substitute. Moreover, the closed upper ends of said flexible members are axially thickened to prevent deformation in action and their side walls are gradually tapered in radial thickness downwardly from the thickened upper ends thereof to the base portions. The tapered thickness of the side walls of each flexible wall member serves to propagate distention progressively upward from the base during a pressure stroke and, conversely, to propagate contraction downward toward the base during a suction stroke, as will be explained more fully hereinafter.

Flexible wall members 156a and 156b are fluid-impervious and sealed so tightly at their bases in the manner already described that they effectively divide the respective casings 143a and 143b into radially inner and outer primary and secondary working chambers 157a—157b and 158a—158b. Obviously, when flexible wall member 156a of lefthand unit A is in its fully contracted condition as shown in Fig. 17, primary working chamber 157a is restricted to the interior chamber of collapse-preventing form 152a, whereas in the righthand unit B, in which flexible wall member 156b is fully distended, primary working chamber 157b will occupy practically the interior space of casing 143b while secondary working chamber 158b will have been reduced to zero capacity.

At the upper ends of casings 143a and 143b, micro-switches 159a and 159b are located for use in connection with the control valve operating circuits (not shown) and have their respective pushbuttons 160a and 160b projecting into the respective secondary working chambers 158a and 158b for triggering contact by the upper ends of flexible wall members 156a and 156b. In order to insure positive and instantaneous switch actuation, the upper ends of flexible wall members 156a and 156b are provided with metallic rings embedded in their outer surfaces for direct, hard pushbutton contact.

Operation of the double-unit pump's flexible wall members will be understood upon reference to Figs. 17, 18 and 19 in that consecutive order. Fig. 17 represents the operational stage at the instant a pressure stroke is commencing in casing 143a and a suction stroke is commencing in casing 143b. In Fig. 18, partial progress in these simultaneous pressure and suction strokes is represented. In the lefthand casing 143a, pressure in primary chamber 157a is distending flexible

wall member 156a. Because the upper portions of the side walls of said member 156a are thicker than the lower portions and because the increase in thickness is graduated, the lower portions will become distended first since they offer the least resistance to radial pressure. Consequently, the complete distention of flexible wall member 156a is propagated steadily upward without any inefficient, fatigue-producing irregularities in flexible wall action. The same thing occurs in reverse order in the opposite suction stroke represented in the righthand casing 143b. In this case, the thicker upper side wall portions of flexible wall member 156b have a stronger contractional tendency than the thinner lower side wall portions, so the contraction is propagated downward in regular progression. Fig. 19 represents completion of the pressure and suction strokes of flexible wall members 156a and 156b in the respective casings 143a and 143b, and, shows the micro-switch 159a in the act of being triggered for control valve reversal.

Figs. 20 to 24, inclusive, illustrate a modified form of the type of pump disclosed in Figs. 17 to 19. In this instance, the complete pump is shown. The casings 161a and 161b differ from casings 143a and 143b of the other embodiment principally in the relative dispositions of the secondary ports and the micro-switches and in the form of flexible wall members 162a and 162b. The upper ends of casings 161a and 161b are closed to form rounded domes 163a and 163b and render the casings generally bottle-shaped, and the secondary ports are located substantially midway between the ends of the casings. In this embodiment of the invention, there are two secondary ports for each casing, i. e. casing 161a and casing 161b have secondary intake ports 164a and 164b, respectively, connected with secondary intake lines I—I, and secondary delivery ports 165a and 165b connected with secondary delivery lines D—D. Because of this arrangement with no intervening control valves, the respective secondary intake and delivery line connections must have suitable check valves (not shown) to prevent retrograde flow therein.

A single double-acting control valve 166 is provided in the base 167 on which casings 161a and 161b are mounted in upright coextensive positions. This control valve has a horizontally elongated valve chamber 168 underlying both casings 161a and 161b and provided with two-way ports 169a and 169b communicating with the lower ends of the respective collapse-preventing forms 170a and 170b. Primary pressure and suction ports 171 and 172 are provided respectively below and above the mid-portion of valve chamber 168 for connection with the respective primary pressure and suction lines 173 and 174. Primary pressure port 171 is branched to communicate with valve chamber 168 through two longitudinally spaced mouths. Similarly, suction port 172 is branched to communicate with valve chamber 168 through longitudinally spaced mouths in vertical registration with the mouths of port 171.

A valve plunger 175 is mounted to slide back and forth longitudinally in valve chamber 168 between the two terminal dwell positions shown in Figs. 20 and 21, respectively. A spring-pressed dwell-latch 176, such as that shown in Figs. 20 and 21 in reduced size and on a large scale in Fig. 24, is provided in control valve 166 to secure valve plunger 175 yieldingly in either dwell position. The bottom face of valve 175 is of such construction and longitudinal extent that it will

cover one mouth of pressure port 171 and open the other mouth thereof to the interior of valve chamber 168 in one dwell position of said plunger and will reverse the connection of port mouths and valve chamber in the opposite dwell position. The upper face of valve plunger 175 has longitudinally spaced channels 177—177 which are so positioned that, in the dwell position wherein pressure port 171 is in communication with port 169a of casing 161a (Fig. 20), suction port 172 will be in communication with port 169b of casing 161b, and, in the opposite dwell position, wherein pressure port 171 is connected with port 169b of casing 161b (Fig. 21), suction port 172 will be in communication with port 169a of casing 161a.

The cores of solenoids 178 and 179 are affixed to opposite ends of valve plunger 175 and are so wound and arranged in electric circuits (not shown) controlled by micro-switches 180 and 181 that shifting of said valve plunger back and forth in synchronization with completion of each pressure stroke by flexible wall members 162a and 162b, respectively, is effected.

It will be observed that both micro-switches are located substantially at the same level as secondary ports 164a—164b and 165a—165b. At this level, the pushbuttons 180' and 181' of micro-switches 180 and 181, respectively, project into the secondary chambers of casings 161a and 161b from contact with the midportions of flexible wall members 162a and 162b, respectively, upon completion of their pressure strokes. In this instance, flexible wall members 162a and 162b both have their side walls centrally thickened and tapered in thickness toward the upper and lower ends thereof. Due to this wall structure, pressure of primary fluid during a pressure stroke will be exerted through the interior of collapse-preventing form 170a or 170b, as the case may be, against both thin end portions of the side walls of the flexible member concerned in the beginning to commence distention in these regions. Thereafter, the distention will be propagated axially inward toward the thickened medial portion. Reverse propagation of contraction progresses endward from the center in a suction stroke.

The operation of this modified form of double-unit pump will now be described. Fig. 20 represents the operational stage wherein lefthand unit A is approaching the end of a pressure stroke and righthand unit B is at the end of a suction stroke. A moment later, when the pressure stroke has been completed, the thickened midportion of flexible wall member 162a will have contacted pushbutton 180' and thereby closed micro-switch 180. When this occurs, control valve 166 will be shifted to the dwell position represented in Fig. 21 to reverse the strokes in the manner shown.

Fig. 25 illustrates a quadruple-unit pump and has been introduced to demonstrate the compact construction which may be achieved when doubling the capacity of the type of pump disclosed in Figs. 20 to 24. Only the general organization of casings of the two double-unit pumps which have been combined is shown. In this embodiment, it is as if a second double-unit pump of that kind were moved into position directly alongside (beneath in Fig. 25) the pump disclosed in Fig. 22. Casings 182a and 182b in Fig. 25 correspond to casings 161a and 161b in Fig. 22. To these casings 182a and 182b have been added the casings 183a and 183b of the sec-

ond pump. The principal departure lies in the rearrangement of the secondary lines and their connection with the various secondary chambers of the quadruple-unit pump. For example, secondary intake lines I—I independently communicate with the secondary chambers of casings 182a and 182b on one side of the pump and with the secondary chambers of casings 183a and 183b on the opposite side, as shown. One Y-shaped delivery line manifold D is connected with the secondary chambers of casings 182a and 183a and a second Y-shaped delivery line manifold D' is connected with the secondary chambers of casings 182b and 183b at the opposite end of the pump. The manner in which this modified pump operates should be obvious without further illustration or description.

It will be understood that it is intended to cover all changes and modifications of the examples of the invention herein chosen for the purpose of illustration which do not constitute departures from the spirit and scope of the invention.

Having thus described the invention, I claim:

1. A high pressure pump of the flexible wall type for operative connection to the pressure and suction lines of a power-giving primary circulation system and to the intake and delivery lines of a secondary conduction system for the fluid to be pumped, said pump comprising: a combined pump casing and valve chamber structure which is closed to the atmosphere; a flexible wall member dividing the pump casing into non-communicating primary and secondary working chambers; said structure having a primary valve chamber closely adjoining the primary working chamber and connected therewith by a two-way port and also having a secondary valve chamber closely adjoining the secondary working chamber and connected therewith by a two-way port; said structure being further provided with primary pressure and suction ports for the primary valve chamber and with secondary delivery and intake ports for the secondary valve chamber; primary valve means in the primary valve chamber to connect the corresponding two-way port alternately with the primary pressure and suction ports; secondary valve means in the secondary valve chamber to connect the corresponding two-way port alternately with the secondary delivery and intake ports; positively acting means for interlocking operation of the primary and secondary valve means in a manner whereby opening of the primary working chamber to the primary pressure port and synchronous opening of the secondary working chamber to the secondary delivery port is effected alternately with opening of the primary working chamber to the primary suction port and synchronous opening of the secondary working chamber to the secondary intake port; and means for intermittently triggering the valve operating means to cause sequential suction and pressure strokes of the flexible wall member.

2. A high pressure pump as defined in claim 1, wherein the triggering means for the valve operating means is actuated by the stroking movement of the flexible wall means.

3. A high pressure pump as defined in claim 1, wherein the triggering means for the valve operating means is actuated by completion of each stroke of the flexible wall member.

4. A high pressure pump as defined in claim 1, which includes means for biasing the flexible wall member for accelerated movement in its suction strokes.

5. A high pressure pump as defined in claim 1, which includes spring means for biasing the flexible wall member for accelerated movement in its suction strokes.

6. A high pressure pump as defined in claim 1, which includes spring means for biasing the flexible wall member for accelerated movement in its suction strokes, said spring biasing means being in the form of a flat spring member disposed on the secondary working chamber side of the flexible wall member and being anchored rigidly in the pump casing structure and bearing flatly against said flexible wall member, said spring member being in its minimum tension condition when it and the flexible wall member are located at the end of the suction stroke.

7. A high pressure pump as defined in claim 1, wherein the flexible wall member is in the form of a circular diaphragm, and wherein spring means is included for biasing said flexible wall member for accelerated movement in its suction strokes, said spring biasing means being in the form of a flat annular spring member disposed on the secondary working chamber side of the flexible wall member and having a base portion anchored rigidly in the pump casing structure and inwardly projecting radial fingers bearing flatly against said flexible wall member, said spring member being in its minimum tension condition when it and the flexible wall member are located at the end of the suction stroke.

8. A high pressure pump as defined in claim 1, wherein the pump casing is elongated and cylindrical in cross-section and wherein the flexible wall member is thimble-shaped and disposed coaxially within the casing with its open end sealed to one end of the casing in registration with the two-way port thereof to divide the same respectively into radially inner and outer primary and secondary working chambers, said flexible wall member being composed of elastic material and being adapted to distend during each pressure stroke and to contract during each suction stroke.

9. A high pressure pump as defined in claim 1, wherein the pump casing is elongated and cylindrical in cross-section and wherein the flexible wall member is thimble-shaped and disposed coaxially within the casing with its open end sealed to one end of the casing in registration with the two-way port thereof to divide the same respectively into radially inner and outer primary and secondary working chambers, said flexible wall member being composed of elastic material and being adapted to distend during each pressure stroke and to contract during each suction stroke, said flexible wall member also being constructed so that its side wall is tapered longitudinally in thickness toward its open end, whereby distention during each pressure stroke is propagated outward from the two-way port which is connected with the primary pressure port and whereby contraction during each suction stroke is propagated inward toward said two-way port.

10. A high pressure pump as defined in claim 1, wherein the pump casing is elongated and cylindrical in cross-section and wherein the flexible wall member is thimble-shaped and disposed coaxially within the casing with its open end sealed to one end of the casing in registration with the two-way port thereof to divide the same respectively into radially inner and outer primary and secondary working chambers, said flexible wall member being composed of elastic material and being adapted to distend during each pressure stroke and to contract during each suction

stroke, and wherein a perforate tubular collapse-preventing form is mounted inside the flexible wall member in communication with the two-way port and is adapted to fit the interior of the said flexible member when in contracted condition.

11. A high pressure pump as defined in claim 1, wherein the pump casing is elongated and cylindrical in cross-section and wherein the flexible wall member is thimble-shaped and disposed coaxially within the casing with its open end sealed to one end of the casing in registration with the two-way port thereof to divide the same respectively into radially inner and outer primary and secondary working chambers, said flexible wall member being composed of elastic material and being adapted to distend during each pressure stroke and to contract during each suction stroke, said flexible wall member being constructed so that its side wall is tapered endward from the medial portion thereof, whereby distention during each pressure stroke is propagated progressively inward from the ends of said flexible wall member toward the center thereof and contraction during each suction stroke is propagated endward from said center, and wherein the secondary delivery and intake ports are disposed opposite to the medial portion of the flexible wall member.

12. A high pressure pump of the flexible wall type for operative connection to the pressure and suction lines of a power-giving primary circulation system and to the intake and delivery lines of a secondary conduction system for the fluid to be pumped, said pump comprising: at least one pair of individual pumping units, each of which units includes a combined pump casing and valve chamber structure which is closed to the atmosphere; flexible wall members dividing the respective pump casings into non-communicating primary and secondary working chambers; said structure having a primary valve chamber closely adjoining the primary working chamber of each pumping unit and connected therewith by a two-way port, and having a secondary valve chamber closely adjoining the secondary working chamber of said unit and connected therewith by a two-way port; said structure being further provided with primary pressure and suction ports for the primary valve chamber of each pumping unit and with secondary delivery and intake ports for the secondary valve chamber of said unit; interconnected primary valve members movable in the primary valve chambers of all pumping units between spaced dwell positions and being adapted in one dwell position to connect the corresponding two-way port of one primary working chamber with the primary pressure port and the corresponding two-way port of the other primary working chamber with the primary suction port, and in the other dwell position to reverse the connections of the respective two-way ports with the primary pressure and suction ports; interconnected secondary valve members movable in the secondary valve chambers of all pumping units between spaced dwell positions and being adapted in one dwell position to connect the corresponding two-way port of one secondary working chamber with the secondary delivery port and the corresponding two-way port of the other secondary working chamber.

ber with the secondary intake port, and in the other dwell position to reverse the connections of the respective two-way ports with the secondary delivery and intake ports; positively acting means for interlocking operation of the primary and secondary valve members in a manner whereby opening of the primary working chamber of one pumping unit to the primary pressure port and synchronous opening of the secondary working chamber of the same unit to the secondary delivery port is effected alternately with opening of the primary working chamber of the other pumping unit to the primary suction port and synchronous opening of the secondary working chamber of the said other unit to the secondary intake port; and means for intermittently triggering the valve operating means to cause sequential pressure and suction strokes of the flexible wall members of all pumping units.

13. A high pressure pump as defined in claim 12, wherein the triggering means for the valve operating means is actuated by the stroking movement of the several flexible wall members.

14. A high pressure pump as defined in claim 12, wherein the triggering means for the valve operating means is actuated by completion of the pressure stroke of each flexible wall member.

15. A high pressure pump as defined in claim 12, wherein the pump casings of the respective pumping units are in the form of flat circular plates adapted to be arranged in axial alignment and close contiguity in a pile formation, said plates having opposed concavities in their adjacent faces to form the primary and secondary working chambers, the flexible wall member for each pair of plates being in the form of a circular diaphragm and having its marginal edge sealed between the marginal portions of said plates.

16. A high pressure pump as defined in claim 12, wherein each pumping unit is composed of a pair of pump casings of circular form arranged in axial alignment and close contiguity in a pile formation, each pump casing being composed in turn of two circular flat plates having opposed concavities in their adjacent faces to form the primary and secondary working chambers, the flexible wall member for each pair of plates being in the form of a circular diaphragm and having its marginal edge sealed between the marginal portions of said plates, adjacent plates of both pairs which constitute a pile being provided with registering intercommunicating ports whereby the inwardly adjacent working chambers form cooperative primary working chambers and the outer working chambers form cooperative secondary working chambers, the respective casing plates being provided with passages leading from the primary working chambers to the corresponding two-way port which communicates with one of the primary valve chambers and with passages leading from the secondary working chambers to the corresponding two-way port which communicates with one of the secondary valve chambers.

LEON J. GEERAERT.
